UNITED STATES PATENT OFFICE.

RICHARD H. RICE, OF LYNN, MASSACHUSETTS.

DESIGN FOR AN AUTOMOBILE-BODY.

46,101.

Specification for Design.

Patented July 14, 1914.

Application filed March 2, 1914. Serial No. 822,069. Term of patent 7 years.

To all whom it may concern:

Be it known that I, RICHARD H. RICE, a citizen of the United States, residing at Lynn, in the county of Essex and State of Massachusetts, have invented a certain new, original, and ornamental Design for Automobile-Bodies, of which the following is a specification, reference being had to the accompanying drawing, forming part hereof.

Figure 1 is a side view of an automobile body embodying my design. Fig. 2 is a rear view of the design.

The salient feature of my design consists of the configuration shown at the right of the dotted line in Fig. 1 and the corresponding configuration of Fig. 2.

I claim:

The ornamental design for an automobile body as shown and described.

RICHARD H. RICE.
